UNITED STATES PATENT OFFICE.

WILLIAM CONQUEST, OF LONDON, COUNTY OF MIDDLESEX, ENGLAND,
ASSIGNOR TO R. HOE & CO., OF NEW YORK, N. Y.

FOLDING-ROLLER FOR PAPER-FOLDING MACHINES.

SPECIFICATION forming part of Letters Patent No. 367,352, dated July 26, 1887.

Application filed June 7, 1884. Serial No. 131,238. (No model.) Patented in England October 31, 1881, No. 4,763.

To all whom it may concern:

Be it known that I, WILLIAM CONQUEST, a citizen of the United States, residing in the city of London, county of Middlesex, England, have invented certain new and useful Improvements in Folding-Rollers for Paper-Folding Machines, fully described and represented in the following specification and the accompanying drawings, forming a part of the same.

10 This invention, which forms the subject-matter of British Letters Patent No. 4,763, A. D. 1881, relates to that part of the machinery for folding sheets of material which is known as the "folding-rollers," and into the bite of a 15 pair of which rollers the material to be creased or folded is tucked by a blade projected between said rollers.

In the operation of folding rollers as heretofore constructed, whether made with polished metal-surfaces or draw-filed surfaces, or wooden roller, or rollers composed of wooden cores covered with felt, it sometimes happens that they either fail to grip the sheet tucked into their bite by the folding-blade or only 25 grip one side of the sheet, resulting in the first instance in the failure to fold the sheet and in the other in delivering the sheet slightly askew, so that it runs out of its proper path.

The object of this invention is to make the 30 action of the folding-rollers in carrying off the sheet or sheets of paper that are tucked into them by the folding-blade more positive than heretofore, and thus avoid the defects and inconveniences above mentioned. To this 35 end each folding-roller is provided with elastic rings of such diameter that they will project slightly beyond the surface of the roller, so that when two companion rollers are placed in working position their elastic rings only

40 will touch. There will thus be a space between the rollers extending from ring to ring in their length, into which the folding-blade may tuck the sheet without pressing against the metal rollers. The folding-blade is made 45 to penetrate a little beyond the breast of the rollers, for which purpose it is cut away where it would meet the rings. The sheets are thus tucked positively into the bite of the elastic rings, and by them is carried forward to receive the next fold or to be delivered.

In the accompanying drawings, Figure 1 is a longitudinal section of a folding-roller and its folding-blade, and shows one method of constructing the same according to this invention. Fig. 2 is a similar view of a folding- 55 roller, showing another mode of applying this invention thereto. Fig. 3 is a cross-section of a pair of companion rollers as if taken on lines corresponding, respectively, to the lines *xx* and *yy* of Fig. 1.

The folding-rollers *B B* are mounted on shafts *A A*, as usual. These rollers may be cast in one piece, as in Fig. 1, or in short lengths, as in Fig. 2. When a roller is cast in one piece, it is preferable to make it at different parts in its length of greater thickness than at others, so that peripheral grooves *a* 60 may be turned in the thicker parts, as fully shown in Fig. 1. Into these grooves, of which there may be two, three, or more in the length 65 of the roller, elastic rings *b b* are sprung. These rings, which I prefer shall be of vulcanized india-rubber, are of somewhat greater external diameter than the roller to which they are to be fitted, so that when two rollers 70 thus fitted with rings are placed together their rings only shall touch the space left between the metal rollers being about equal to or slightly in excess of the thickness of the 75 roller.

The folding-blade *C* is notched, as at *c*, (see Fig. 1,) to allow of the blade clearing the rings when descending between the rollers, and thus insuring that the rings shall take hold of the creased material or sheet to carry 80 the same forward. When the folding-rollers are constructed of short lengths, an elastic disk, *d*, is placed between adjacent lengths, as shown at the right hand of Fig. 2.

The folding-roller may consist of two lengths 85 of roller, which is the preferred form, in which case a combination of elastic rings *b* and elastic disks *d* is employed, as shown in Fig. 2. In this form the castings, being shorter than in the arrangement shown in Fig. 1, are more 90 likely to be true, and therefore the labor of turning up will be materially diminished.

What is claimed is—

1. The combination, with the folding-rollers of folding-machines, of elastic gripping-bear- 100

ings, as *b d*, projecting beyond the general surface of the rollers, substantially as shown and described.

2. In a folding-machine, folding-rollers constructed in sections, with interposed disks of elastic material projecting beyond the general surface of said rollers, substantially as described.

In testimony whereof I have hereunto set my hand in the presence of two subscribing witnesses.

WILLIAM CONQUEST.
